MORTON HARLOE, OF HAWLEY, PENNSYLVANIA, ASSIGNOR OF ONE-HALF
TO WILTON S. BLOES, OF PECKVILLE, PENNSYLVANIA.

INSULATOR FOR ELECTRIC WIRES.

SPECIFICATION forming part of Letters Patent No. 669,691, dated March 12, 1901.

¹Application filed September 19, 1900. Serial No. 30,489. (No model.)

To all whom it may concern:

Be it known that I, MORTON HARLOE, a citizen of the United States, residing at Hawley, in the county of Wayne and State of Pennsylvania, have invented certain new and useful Improvements in Insulators for Electrical Wires, of which the following is a specification, reference being had therein to the accompanying drawings.

10 This invention relates to insulators for electrical conduction-wires, and has for its objects to provide such insulator in a simplified form, to dispense with the necessity of tying the insulated wire, and to provide greater preservation for the wire insulated and other objects, as herein set forth, and more fully pointed out in the claims.

In setting forth the invention reference is had to the accompanying drawings, forming 20 a part of this specification, in which similar characters of reference denote like and corresponding parts in the several views.

Figure 1 is a side elevation of parts of one of my insulators, the upper and lower parts being partially separated to more fully show the construction thereof. Fig. 2 is a view, partly in cross-section, taken on the line $x x$ of Fig. 1 when all the parts are assembled. Fig. 3 is a top view of one of my insulators, 25 partly in cross-section, on the line $y y$ of Figs. 2 or 5 and showing in dotted lines one of the motions of the device requisite in fastening the wires thereto. Fig. 4 is a substitute form of my device when constructed from a solid 30 piece of glass or porcelain instead of being provided with a wooden standard, as in Figs. 1 and 2. Fig. 5 is a view, partly in cross-section, taken on the line $t u$ of Fig. 4. Fig. 6 is a general view of my device in use, showing it in both horizontal and vertical positions.

40 Referring to Figs. 1 and 2, my insulator is constructed from two main pieces A and B, the base-piece B being preferably constructed from wood and having a flat side or bottom 45 adapted to sit on a flat surface and to remain slidable thereon during the use of the device. This base-piece B is screwed to the surface of its support by means of a screw C, which extends downward through it at one side of its 50 center through the hole B. This base-piece is further provided with a screw-threaded

shank E, adapted to engage with the inwardly-screw-threaded portion F of the upper or main piece A, which piece is adapted to be screwed fast to the base-piece B and to turn there- 55 with after insertion of the screw C to its place, the said screw being the only means of securing the insulator to its position. The main piece is particularly constructed with a circuitous groove or cut G, winding in a zigzag 60 shape partially under the cap H of the main part and also cutting under projections I I' of the main piece A. This groove in the particular form of my invention here shown is designed to make three angles in the wire se- 65 cured to the insulator, one main angle J curving around the stud K and minor angles j j, where the wire L is pressed under the projections I I'. The main portion of my insulator is also provided with a neck M, to which 70 a tying-wire may be secured and the wire attached as in the ordinary form of insulators now in use. This groove is also particularly required where it is desired to run a branch wire from the main at any point of insulation. 75 The tension may thus be applied to the main body of the insulator without straining the upper part thereof, which is intended for the main line only.

In the substitute form of my insulator 80 (shown in Figs. 4 and 5 specially) the main part thereof is hollowed out at N in order to economize in the material for making the same and the fastening-screw O extends from the top of the insulator through to the base, 85 being fastened as described for the form in which the base is made of wood and remaining slidable or revoluble on the screw for the same purpose. This form dispenses with the wooden base entirely. In both forms the in- 90 sulator is petticoated, as at P and P'. In the substitute form the petticoat is constructed by the groove Q extending around the main body of the insulator, forming the overhanging portion or petticoat P'.

95 The operation of the device may now be more fully explained. In connecting a wire to the insulator the insulator is swung side- wise on the vertical screw O as a center until the wire L may be laid into one portion of the 100 groove G, heretofore described, as shown in Fig. 3. The insulator is then swung in the

direction of the arrow, the projection I' extending over the wire L and forming the bend J' therein, this being at the taut side faced toward the already-fastened end of the wire L.

5 The other loose end is now bent into the angle J, around the inner angle of the stud K, and pressed around into the opposite end of the groove G and under the projection I, when the hand may be released from the wire L

10 without danger of its slipping from its fastenings; but the insulator before the opposite end of the wire is fastened will naturally sag or swing toward the point of greatest tension, which will be corrected when the next

15 fastening in advance is made during the course of stringing the wires.

The crown or cap H has projecting ends h h, adapted to assist in guiding the wire into its place during the process of stringing. It also

20 projects forward at h' to form an overhanging projection to assist in keeping the wire L in its place during any great agitation thereof. It overhangs sufficiently so that, taken in connection with the projections I and I', the wire after being once inserted cannot be

25 removed without either breaking off the projections or finding considerable more slack than is likely to be left by accident in stringing the wire.

30 This specification discloses two particular forms of insulator embodying my invention. It is evident that many of the details may be varied without departing from the general spirit thereof.

35 Having thus described my invention, what I claim, and desire to secure by Letters Patent, is—

1. An insulator having a body portion with means for mounting it to swing, the body portion having located thereon a stud capped with an overhanging flange, a circuitous groove winding between said capped stud and oppositely-directed projections, into which groove the wire to be insulated is adapted to

40 be bent and to be retained by the projections

45

and capped stud aforesaid, and an upwardly-cut groove extending around the body portion forming a petticoat thereon, substantially as specified.

2. An insulator having a body portion constructed from two separate pieces, a lower or base piece adapted to be mounted eccentrically by a vertical screw or pin securing the same loosely to any suitable support, together with a top piece adapted to be screwed to the base-piece aforesaid and rigidly fastened thereto and adapted to swing therewith eccentrically in the operation of lining the wire to be insulated, the said top piece being provided with a circuitous groove cut through the body thereof, and the wire to be insulated adapted to be secured within the said groove, substantially as specified.

3. An insulator having a body portion constructed from an upper and lower piece adapted to be screwed together and means formed on the upper body portion around which the wires to be insulated may be bent to secure the wire, such means being capable of engaging the wire, to bend the same as the insulator

65

70 is swung first to one side and then to the other.

4. The herein-described insulator consisting of a body portion having an eccentric vertical bore therethrough and a pin adapted to

75

pass therethrough and secure the same, the said body portion being provided with a neck adapted to receive tying-wire, and also with a circuitous groove and projections on the body thereof adapted to secure and hold the main

80

85 or line wire in combination with an upwardly-cut groove forming a petticoat on the said body portion, substantially as specified.

In testimony whereof I affix my signature in presence of two witnesses.

MORTON HARLOE.
